PAIR OF SUNGLASSES

Charles A. Baratelli, Reading, Pa., assignor to Pennsylvania Optical Company, Reading, Pa., a corporation of Pennsylvania

Filed Apr. 6, 1964, Ser. No. 79,358

Term of patent 14 years

(Cl. D57—1)

FIG. 1 is a front perspective view of a pair of sunglasses showing my new design.

FIG. 2 is a front elevational view;

FIG. 3 is a top plan view; and

FIG. 4 is a side elevational view.

I claim:

The ornamental design for a pair of sunglasses, as shown.
